UNITED STATES PATENT OFFICE.

FRANK D. MOON, OF ENGLEWOOD, NEW JERSEY.

SELF-LOCKING CLIP.

1,271,350.

Specification of Letters Patent. Patented July 2, 1918.

Application filed February 1, 1918. Serial No. 214,872.

To all whom it may concern:

Be it known that I, FRANK D. MOON, a citizen of the United States, and a resident of Englewood, in the county of Bergen and State of New Jersey, have invented a new and Improved Self-Locking Clip, of which the following is a full, clear, and exact description.

This invention relates to building construction and has particular reference to means for attaching corrugated sheets of metal, or their equivalent, to metal supports or channels in the erection of metal buildings.

Among the objects, therefore, of the invention is to improve the attachment clips for securing the corrugated sheets to roof purlins whereby the roofing sheets may be attached rapidly and securely to the purlins and with the minimum amount of danger or labor on the part of the operators.

A further object of the invention is to provide a clip that shall be self locking with respect to its engagement with the upper or outer flange of a channel shaped purlin and which when attached and with the sheet secured thereto shall be held from any possible displacement from the purlin flange in any direction.

Another object of the invention is to provide an attachment clip for corrugated sheets that may be attached in such a manner as to prevent all possibility of rattling of the sheets, either as roofing or siding.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which

Figure 1 is a diagram representing a portion of a metallic roof and siding illustrating my improvement.

Fig. 2 is a plan view of the sheet metal clip in its flat form prior to bending into arch shape.

Fig. 3 is a side elevation of the clip indicating the manner of applying it to or over a channel flange.

Fig. 4 is a central longitudinal section

of the special clip applied to the lowermost purlin having its upper flange at an angle to the plane of the roof sheets.

Fig. 5 is a sectional view of one of the regular clips for securing either a roof or siding sheet to a metal support, the face of the supporting member being substantially parallel to the plane of the sheet.

Fig. 6 is an end elevation of a clip of the character shown in Fig. 5 indicating its cross sectional form and relation to the supporting flange and sheet connected thereto; and

Fig. 7 is a view of the character of Fig. 6 but indicating a slightly modified form of clip.

Referring now more particularly to the drawings I indicate generally in Fig. 1 the object or nature of the invention with respect to a metallic building including a post 10, rafters 11 and any desired number of horizontally extending angle girts 12 and purlins 13 and 14 to which siding and roofing sheets 15, preferably of corrugated metal, are connected by means of the special clips which *per se* constitute this invention.

I will first describe the construction and operation of the standard clip with reference particularly to Figs. 2, 3, 5 and 6. The clip as a whole is indicated at 16 and is made from a single piece of strong stiff sheet material such as a good quality of galvanized iron or other suitable or equivalent material. Fig. 2 shows the flat form of the clip after it is stamped out but before it is bent into the arch shape in which it is used in practice as shown in the other figures. The clip comprises a body portion 17 which in its operative form constitutes a rigid channel and with respect to corrugated sheeting projects into one of the corrugations and lies therein parallel to the corrugation and between the crest thereof and the supporting member to which the clip is connected and serves to secure the sheeting.

Broadly speaking and irrespective of the specific construction of the clip body it is provided at one end with a hook for extension inward and embracing engagement around the free edge 18 of the flange 19 of either a roof purlin, siding girt or any other supporting member having a flange corresponding to the building elements illustrated. At the other end the clip is provided with a spur or analogous engag-

ing means to snugly embrace or engage over the outside of the flange and preferably just below the base portion thereof as indicated at 20. When the clip is constructed of sheet metal in the manner illustrated in Figs. 2 and 6 it comprises two of the aforesaid hooks indicated at 21 spaced from each other in a direction of the flange and embracing therefore two spaced points 5 or portions of the flange, and likewise the hooks indicated at 22 are preferably duplicated for spaced engagement with the base portion of the flange. It is to be understood, however, that the particular number 10 or arrangement of these engaging and interlocking features are subject to considerable variation in scope so long as the general principles herein enunciated and claimed are not departed from.

15 With the clip body bent into arch shape as shown in Fig. 6 so that the points of the hooks 21 are brought into transverse alignment, as are also the spurs 22, the manner of application and use of the device will be 20 appreciated. The hooked portion 21 of the clip is first projected inward so as to engage over or embrace the free edge 18 of the flange as shown in Fig. 3, the sides of the body above the points of the hooks being cut 25 out as indicated at 23 to provide a clearance for the admission of the extreme edge of the flange. The clips are made of standard sizes to coöperate with standard sizes of structural flanges, and after the application of 30 the hooked portion of the clip as shown in Fig. 3 the points 22' of the spurs are forced downward or inward over the edge or angle at the base 20 of the flange. The clip is so designed that the spurs in this action may 35 have some gripping action over the outside of the flange and with the points 22' thereof having a bearing contact against said base. From this description it will be appreciated that the hook or hooks serve immediately 40 two purposes, to prevent movement of the clip toward the base 20 and to prevent movement of the hooked end of the clip upward or outward from the flange. The spur or spurs 22, so long as they are in interlocking 45 engagement with the base of the flange serve as a positive means to prevent displacement of the clip such as would permit the disengagement of the hook or hooks, and when the attachment is completed as described below 50 there can be no disengagement of the spur or spurs from the base of the flange.

55 At any desired place between the hook and the spur portions of the clip I provide on the sides of the clip, when made of sheet metal as illustrated or when made of other material at any convenient place, one or more contact points 24 to bear directly and squarely against the plane outer face of the flange when the attachment is applied. I 60 preferably arrange these contact points 24

relatively close to the active points of the hooks 21.

The hooked end portion of the body is provided with a hole or slot 25 preferably in the longitudinal center of the body and upward or outward from the free edge 18 of the flange through which any suitable binding fastener such as a screw bolt 26 having a nut 27 may be passed for attaching a crest of one corrugation of the sheet 70 15 to the clip while the inwardly directed corrugations lie directly in place upon or against the outer face of the flange. I also preferably employ a soft metal washer 28 between the outer end or head of the fastener 80 and the sheet to make a watertight joint in accordance with the usual practice. In the practice of my invention the effective height of the arch of the clip, see Fig. 6, between the outer face of the flange and the inner 85 surface of the crest 8 of the corrugated sheet 15 is appreciably less than the height of the said crest, so that when the binding fastener 26 or its equivalent is passed through the sheet and crown of the arch and tightened, 90 said fastener has the effect of binding the parts firmly toward each other but still leaving a slight space between the sheet and said crown. This results in the provision of a most effective fastening and obviates any 95 possibility of rattling of the sheets. The action of the fastener furthermore drawing the crest of the corrugation down toward the flange and reacting to draw the hooked end of the clip upward or outward into firm 100 engagement with the inner face of the flange tends to tilt the spurred end of the clip inward until the contact point or points 24 come into secure supporting engagement with the outer face of the flange. It will 105 thus be seen that a clip made in accordance with the disclosure herein is not only adapted to lock itself upon the angle flange and so be held from accidental displacement during the operation of attaching the corrugated sheets, but also will prevent any possible movement of the attaching means laterally or outward with respect to the flange.

The form of the device shown in Figs. 2, 3 and 5 is adapted for the attachment of a sheet that lies directly against the flange and irrespective of the inclination of the plane in which the inner face of the sheet engages the outer face of the flange, but for the attachment of the lower ends of the roofing sheets to the purlin 13 whose upper face is horizontal I provide a slightly modified form of clip 16' the body portion of which may be regarded as wedge shaped or triangular according to the angle of inclination 115 of the plane of the roof. Otherwise the construction and operation of this clip 16' are the same as has already been described in detail, and hence the interlocking features 120 thereof are of the same form and action and 130

bear the same reference characters as are applied to the standard form.

The type of fastener illustrated is found to be very satisfactory because of its convenience and rapidity of application. A workman from his position on the outside of the sheet may easily reach under or within the same so as to hold with the fingers of one hand the nut 27 in position to apply the screw bolt thereto with the fingers of his other hand. Then with the application of a screw driver the tightening of the fastener may be quickly completed, the shape of the arch of the clip adapting itself naturally to prevent the rotation of the nut. This action is satisfactory ordinarily with respect to any form of the arch whether rounded or angular as shown in Fig. 7. Fig. 7 shows a structure in which the nut, however, is held

more positively from rotation because of the angular structure of the arch indicated at 16^a, but otherwise the details of construction and advantages of this clip are or may be the same as already described.

Inasmuch as the point of attachment through the fastener 26 is upward or beyond the flange it is to be noted that two practical conditions obtain as follows: First since there is no possibility of the fastener striking the flange it is not necessary to provide a fastener of any particular or specified length, a feature of importance when it is considered that the fasteners must be long enough in practice to secure at some points as many as four sheets together and hence if the same length of fastener be used where only one sheet is attached there might otherwise be the possibility of the fastener being too long if the fastener were directed toward the flange. Again, since the fastener is upward or beyond the flange provision is afforded for the application of a tool in case the fastener were of a different type, such for instance as a rivet to be upset.

At a, Fig. 2, I indicate in dotted lines the fact that the type of my clip when made of sheet metal, or its equivalent, adapts it to be stamped by means of dies of a size adapting it for application to a narrow flange and when the same clip is required to be applied to a wider flange those portions of the spurs included in the dotted lines may by means of any simple or suitable tool be clipped off. Ordinarily, however, the clips are made in all various standard sizes for direct application without fitting.

Referring again to the spur portion of the clip, while the clips are made in standard sizes which because of the manner of making are uniform in dimensions, it is well known that the width of the flanges of structural shapes vary somewhat, sometimes as much as one eighth of an inch. It is to be noted, therefore, that while the length of the clip between the hook and the spur is practically

equal to the width of the flange, in practice such length may be slightly more or slightly less than the width of the flange. In either event it is a matter of minor consequence for two reasons: First, if the clip is slightly short it still may be forced or driven down into place because the points 22' of the spurs may bend or bur or the spurs themselves may spring slightly to this end, and secondly, if the clip should be slightly loose in its fit upon the flange no harm can result because the spurs will still prevent the displacement of the hooks from the free edge of the flange. In this connection it will be borne in mind that the contacts 24 are intended to sustain the primary gripping engagement in connection with the contact portions of the hooks.

I claim:

1. The combination with a flanged support and a sheet, of a clip to secure the sheet to the support comprising a member having at one end a hook embracing the free edge of the support flange, the opposite end of the member engaging over the base of the flange, and a fastener serving to connect the sheet with the hooked end of the member and tending to force said opposite end of the member firmly against the base and away from the sheet while drawing the hooked end toward the sheet.

2. The combination with a flanged support and a sheet, of a clip to secure the sheet to the support comprising a member having at one end a hook embracing the free edge of the flange and having bearing contact with the inner face thereof, said member having another portion engaging over the base of the flange to prevent slippage of the hook from the free edge, and fastening means serving to connect the sheet to the clip and tending to tilt the clip around said bearing contact whereby said other portion is prevented from separating from its engaging position.

3. The combination with a flanged support and a corrugated sheet supported against the same, of a clip spanning the support flange and having three points of contact with said flange, one within the free edge of the flange and the other two on the outside of the flange, one portion of the clip extending into one of the corrugations, and fastening means serving to connect said extending portion of the clip to the adjacent crest of the corrugation and acting to maintain the clip in contact with the flange at the three points indicated.

4. The combination with a support having a flange with a free edge and an angle at the base of the flange and a corrugated sheet lying against said flange, of a clip to fasten the sheet to the support and comprising a member projecting from the flange into a corrugation, one end of the clip projecting

- inward from the corrugation around the free edge of the flange, a portion of the clip remote from said end engaging on the outside of said angle, and a portion of the clip between the angle and the free edge of the flange bearing against the outside of the flange, and fastening means between the sheet and the inwardly projecting end of the clip and acting to draw the first mentioned end outward into the corrugation and against the inner face of the flange and at the same time force the other two portions of the clip firmly against the outside of the base and flange.
5. As an article of manufacture, a clip to fasten a sheet to a flanged support, said clip comprising a pair of hooks to embrace the free edge of the flange and spaced from each other in a direction lengthwise of the flange, said clip including a portion engaging the outer surface of the flange, and the end portion of the clip remote from the hooks and portion engaging the flange being provided with a hole for attachment of the sheet.
10. As an article of manufacture, a clip to fasten a sheet to a flanged support, said clip comprising a pair of hooks to embrace the free edge of the flange and spaced from each other in a direction lengthwise of the flange, and means carried by the clip to engage the outside of the flange to prevent the disengagement of the hooks from the flange edge.
15. As an article of manufacture, a clip to fasten a sheet to a flanged support, said clip comprising a rigid body portion having at one end a hook to engage around and within the free edge of a flange providing an outwardly acting bearing point, said body be-
- ing provided remote from the hook with means to engage and bear inward against the outer face of the flange, there being provided an opening for a fastening member through the hooked end of the clip outward from the free edge of the flange, substantially as set forth.
20. The combination with a flanged support and a sheet applied thereto, of a fastening clip between the sheet and the flange to secure the sheet to the flange, said clip comprising spaced contact portions bearing on the inner and outer faces of the flange, the inner contact portion being closer to the free edge of the flange than the outer contact portion, and binder means extending from the sheet into engagement with the end of the clip remote from the edge of the flange and serving to tilt the clip with respect to the flange causing thereby both of said contact portions to firmly grip the flange.
25. The combination with a flanged support and a corrugated sheet supported thereon, of a fastening clip between the sheet and the flange to secure the sheet to the flange, said clip projecting into one of the corrugations of the sheet and comprising spaced contact portions bearing on the inner and the outer faces respectively of the flange, the outer contact portion extending farther from the free edge of the flange than the inner contact portion, and binder means extending from the crest of the corrugation in which the clip is located into engagement with the end portion of the clip remote from the edge of the flange, substantially as set forth.

FRANK D. MOON.
